CLAIM

The ornamental design for a charger, as shown and described.

DESCRIPTION

FIG. 1 illustrates a top perspective view of a charger showing my new design;

FIG. 2 illustrates a back elevational view thereof;

FIG. 3 illustrates a right side elevational view thereof;

FIG. 4 illustrates a left side elevational view thereof;

FIG. 5 illustrates a top plan view thereof;

FIG. 6 illustrates a bottom plan view thereof; and,

FIG. 7 illustrates a front elevational view thereof.

The broken lines in the drawings are for the purpose of illustrating portions of the charger that form no part of the claimed design.

1 Claim, 7 Drawing Sheets
